UNITED STATES PATENT OFFICE

93,400

DESIGN FOR A TYPEWRITER

Rixford U. Jennings, Buffalo, N. Y.

Application May 1, 1934, Serial No. 51,614

Term of patent 7 years

To all whom it may concern:

Be it known that I, RIXFORD U. JENNINGS, a citizen of the United States of America, residing at Buffalo, in the county of Erie and State of New York, have invented a new, original, and ornamental Design for a Typewriter, of which the following is a specification, reference being had to the accompanying drawing forming a part thereof.

In the drawing:

Fig. 1 is a perspective view of a typewriter showing the new design, and
Fig. 2 is a plan view.

I claim:

The ornamental design for a typewriter, as shown.

RIXFORD U. JENNINGS.
